UNITED STATES PATENT OFFICE.

GURDEN ROBINSON, OF GRANT, MICHIGAN, ASSIGNOR OF ONE-HALF TO WARD SHATTUCK, OF GRANT, MICHIGAN.

HOSPITAL BED.

Application filed June 24, 1925. Serial No. 39,341.

This invention appertains to hospital beds and the primary object of the invention is to provide such a bed, which can be adjusted so as to permit the body portion thereof to 5 assume different angles, which will be best suited for the patient using the bed.

Another object of the invention is to provide a hospital bed embodying a body or spring movable relative to the frame of the 10 bed at different angles, and a movable head piece for the body or spring which can be set at different angles to the main portion of the spring, the adjustability of the body or spring and the head piece permitting a combination 15 of adjustments to be had, which will meet with the varying conditions of different patients.

A further object of the invention is to provide a novel means for associating the body 20 or spring with the frame of the bed, a novel means for adjusting the body or spring relative to the frame of the bed and the head of the spring relative to the main portion thereof, whereby the bed can be adjusted in 25 a minimum amount of time and with a minimum amount of energy.

A further object of the invention is to provide means for detachably locking the 30 swinging head section of the spring with the main body portion of the spring, whereby the head section can be adjusted independently of the main portion of the spring or moved with the main portion of the spring when locked thereto.

A still further object of the invention is 35 the provision of novel means of associating the spring with the adjusting means therefor, whereby the spring can be readily removed from the frame and adjusted when necessary or desirable.

A still further object of the invention is to provide an improved hospital bed of the above character, which will be durable and efficient in use, one that will be simple and 40 easy to manufacture and one which can be placed upon the market at a reasonable cost.

With these and other objects in view, the invention consists in the novel construction, arrangement and formation of parts, as will 45 be hereinafter more specifically described, claimed, and illustrated in the accompanying drawings, in which drawings:

Figure 1 is a side elevation of the improved

hospital bed, showing one of the adjusted 55 positions of the body or spring thereof in dotted lines,

Figure 2 is a longitudinal section through the frame of the bed, showing the head section of the spring in its adjusted position relative to the main portion of the spring, 60

Figure 3 is a top plan view of the improved bed,

Figure 4 is a rear end elevation of the bed, parts of the frame thereof being shown in section,

Figure 5 is a transverse section of the bed taken on the line 5—5 of Figure 3 looking in the direction of the arrows,

Figure 6 is a fragmentary detail perspective view illustrating the means for associating one of the adjusting shafts with the frame of the bed and the novel adjusting or lifting arms connected therewith,

Figure 7 is a detail longitudinal section through the bed illustrating the means for 75 mounting the adjusting shaft for the head portion of the spring in position,

Figure 8 is a fragmentary detail perspective view illustrating the means for connecting the movable head section of the spring 80 with the main body portion thereof,

Figure 9 is a fragmentary plan view of the frame of the bed showing the arrangement of the adjusting mechanism for the head section,

Figure 10 is a detail section taken on the line 10—10 of Figure 2 showing the means of connecting the lifting arms to the movable head section of the frame,

Figure 11 is a fragmentary perspective 90 view illustrating the arrangement of the lifting arms for the head section with the adjusting cross rod for the spring.

Referring to the drawings in detail, wherein similar reference characters designate corresponding parts throughout the several views, the letter A generally indicates the improved hospital bed, which comprises a frame 15 which can be constructed substantially the same as ordinary iron or hospital beds. As shown the frame 15 includes the head and foot sections 16 and 17 connected by the longitudinally extending side rails 18.

The head and foot pieces 16 and 17 are preferably formed from tubing and the legs thereof can be provided with suitable casters 21.

Arranged within the frame 15 is the novel bed spring 25 which includes a main body portion 26 and a movable head section 27. The main body portion 26 of the spring 25 includes end bars 28 and 29 which can be formed of angle iron and these bars 28 and 29 have rigidly connected thereto the longitudinally extending side rails 30. These side rails 30 each preferably include a 10 pair of spaced parallel flat bars or straps 31 and the terminals of the angle bars 28 and 29 can be provided with depending attaching lugs 32 which can be disposed between and riveted to the said straps 31. The position of 15 the lugs 32 between the straps hold the same in a spaced parallel condition, for a purpose, which will be hereinafter more fully described. The body of the spring is made up of a plurality of links 33 and the end links 20 are connected by means of coiled springs 34 with suitable attaching bars 35 connected in any preferred manner to the end bars 28 and 29. While I have shown a particular type of 25 spring body connected to the frame with springs, it is to be understood that any desired type of spring body can be utilized.

The movable head section 27 of the spring 25 embodies side arms 36 which are of a substantially U-shape in cross section. The 30 outer ends of these arms 36 are connected by a transverse cross bar 37. The arms 36 are adapted to be normally positioned between the parallel straps 31 forming the side rails of the frame of the spring 15 and the arms 35 are rockably connected to said longitudinal side bars 30 by means of pivot pins 38 extending through the said parallel straps 31. Angularly extending legs 39 are formed on the inner ends of the arms 36 and normally 40 extend below the longitudinal side rails 30. These legs 39 carry a U-shaped transverse cross bar 40 the ends of which are engaged by clips 41 formed on the legs 39. This insures the movement of the U-shaped trans- 45 verse cross rod 40 with the head section 27 during the swinging movement thereof. This rod 40 has connected thereto loops 42 which in turn carry a cross rod 43 having arranged thereon a plurality of rings 44. 50 These rings 44 have connected thereto links 45 forming a part of the spring bottom of the bed. At the foot of the bed the links 45 are connected by means of coil springs 46 with the supporting strap 35, while at the 55 head of the bed the links are connected by means of coil springs 47 with the transverse cross bar 37 of the said swinging section 27.

In order to permit the free swinging move- 60 ment of the head section 27 the links forming the head section are extended between the links forming the main spring bottom of the spring 25.

In order to raise and lower the head sec- 65 tion 27, lifting arms 48 are provided. These

lifting arms 48 are extended through the parallel bars 31 of the side rails of the spring bottom and have their lower terminals secured to or formed on gear wheels 49 which mesh with gear wheel 50 carried by a trans- 70 verse shaft 51. The gears 49 and 50 are arranged between depending extensions 52 formed on the side rails of the frame of the bed and straps 53 and the extensions 52 and 53 support short stub shafts 54 which rotat- 75 ably receive the gears 49. The straps 53 and the extensions 52 form bearings for the trans- 80 verse shaft 51 and the central portion of this shaft receives a rigid frame 55 which is bolted to the end rail 20 of the bed frame. 85 This frame 55 rotatably supports a downwardly inclined drive shaft 56 having formed thereon or secured thereto a worm 57 which meshes with a sector worm wheel 58 keyed to the shaft 51.

Disposed in spaced parallel relation to the shaft 51 is the operating shaft 59 which is rotatably mounted in suitable bearings carried by the longitudinal side rails 18 of the bed frame. This shaft 59 has secured thereto a 90 beveled gear 60, which meshes with a beveled gear 61 secured to the inclined shaft 56. Hand wheels 62 are carried by the opposite ends of the shaft 59 so as to permit the operation of the shaft from either side of the bed. 95 It is obvious that by turning the shaft 59 that the lifting arms 36 can be raised or lowered according to the direction of rotation of the said shaft 59. If the arms 48 are swung to a raised position, the head section will be ele- 100 vated and the legs 39 will be brought downward pulling on the springs 45 insuring the proper tensioning thereof irrespective of the position of the said swinging head section. The head angle bar 29 of the frame of the 105 spring bottom 25 has formed thereon at spaced points barrels 63 and when the head section 27 is in its extreme lower position in parallel relation to the main frame of the spring bottom, barrels 64 formed on the connecting bar 37 of the head section are adapted to align with the barrels 63. By inserting connecting pins 65 through the barrels 63 and 64 the swinging head section is locked with the main frame of the spring bottom and thus upon turning of the shaft 59 the entire 110 spring bottom can be raised or lowered at the head of the bed.

To prevent the losing of the pins 65 the same can be united by means of flexible chains 115 56 with suitable brackets 67 secured to the end connecting bar 29 of the main frame of the spring bottom.

While if preferred the lifting arms 48 can be made removable from the head section 27, 120 I have formed the upper end of these lifting arms with substantial ball shaped bearing heads 68 and the U-shaped arms 36 are flared as at 69 to form a guide for the said ball shaped bearing heads 68. This permits ef- 125 130

fective raising and lowering movement of the head section relative to the spring body.

In order to adjust the foot end of the spring bottom a transverse operating shaft 70 is provided. This shaft 70 is rotatably mounted in suitable bearings carried by the side rails 18 of the bed and the shaft has formed therein or secured thereto a sector worm wheel 71 meshing with a worm 72 formed or secured to an operating shaft 73. This shaft 73 is rotatably mounted in a suitable bracket 74 carried by the frame of the bed. The shaft 73 extends between the foot of the bed and has affixed thereto a suitable manipulating hand wheel 75. Keyed or otherwise secured to the shaft 70 are the raising arms 76 for lifting the foot end of the spring body and these arms 76 are adapted to lie between the spaced parallel bars 31 of the frame 30 of the spring bottom. As clearly shown in Figure 6 of the drawings, the arms 76 are provided with hooks 77 for engaging the said side bars 31 of the frame. By manipulating the hand wheel 75 the foot end of the bed can be raised, so that the spring bottom will be tilted forwardly and by raising the head section 27 various combinations of adjustment can be had. By locking the head section with the head end of the spring bottom frame and by manipulating both the shafts 59 and 70, the entire spring bottom can be raised. By simply manipulating the shaft 59 and locking the head section 27 to the spring bottom frame, the bottom frame can be tilted downwardly toward the foot end.

Side links 80 can be pivotally secured to the side bars 30 of the main body portion 26

of the spring bottom 25, at a point intermediate their ends and these links 80 can be rockably mounted on the shaft 70 and serve the function of preventing side sway of the spring relative to the frame of the bed.

From the foregoing description, it can be seen that a novel hospital bed has been provided of an exceptionally simple and durable construction, in which the angle of the spring bottom frame can be readily changed.

Changes in details may be made without departing from the spirit or scope of this invention, but:

What I claim as new is:

1. In a hospital bed, a bed frame, a bed spring for the frame including a main body extending the full length thereof having end rails and side rails, each side rail consisting of spaced longitudinally extending straps, a head section extending over a portion of the main body including side arms pivoted between the straps of the side rails and an end rigid bar, lifting arms rockably carried by the frame and extending longitudinally thereof between the straps of the side rails and slidably engaging the arms of the head section, and means for detachably locking the head section with the main body.

2. A bed comprising end rails, links connected to the end rails, a head section pivotally mounted and having a cross bar arranged adjacent one of the end rails, other links connected to the cross bar and other end rail and arranged between said first links, and means for raising and lowering the head section.

In testimony whereof I affix my signature.
GURDEN ROBINSON.
